ABSTRACT OF THE DISCLOSURE

This specification discloses treatment of water discharged from a hot water process for separating bitumen from tar sands. The treatment comprises agglomerating clay dispersed in the water, alternately freezing and thawing the water into a sludge layer and a clarified water layer. The clarified water layer is substantially reduced in clay content compared to the water discharged from the hot water process and is suitable for recycle or discard.

This invention relates to a process for clarifying water discharged from a hot water process for separating bitumen from tar sands. It has been found that agglomeration followed by freezing and thawing can be applied to clay and silt containing water discharges to produce a clarified water suitable for recycle as at least a portion of the feed water to the hot water process.

Numerous deposits of bituminous tar sands exist throughout the world. The most extensive deposits are found in northern Alberta, Canada. The sands are composed of a siliceous materials, generally having a size greater than that passing a 325 mesh screen, saturated with a relatively heavy, viscous bitumen in quantities of from 5 to 21 weight percent of the total composition. More typically, the bitumen content of the sands is between about 8 to 15 percent. This bitumen is quite viscous and contains typically 4.5 percent sulfur and 38 percent aromatics. Its specific gravity at 60° F. ranges typically from about 1.00 to about 1.06. The tar sands also contain clay and silt. Silt is defined as mineral which will pass a 325 mesh screen but which is larger than 2 microns. Clay is mineral smaller than 2 microns including some siliceous material of that size.

There are several well-known processes for effecting separation of bitumen from the tar sands. In the hot water method, the bituminous sands are jetted with steam and mulled with a minor amount of hot water at temperatures in the range of 140° to 210° F. The resulting pulp is conducted to a sump where it is diluted with additional hot water and carried to a separation cell maintained at a temperature of about 150° to 200° F. In the separation cell, sand settles to the bottom as tailings and bitumen rises to the top in the form of an oil froth. An aqueous middlings layer containing some mineral and bitumen is formed between these layers. A scavenger step may be conducted on the middlings layer from the primary separation step to recover additional amounts of bitumen therefrom. This step usually comprises aerating the middlings as taught by K. A. Clark, "The Hot Water Washing Method," Canadian Oil and Gas Industries 3, 46 (1950). These froths can be combined, diluted with naphtha and centrifuged to remove more water and residual mineral. The naphtha is then distilled off and the bitumen is coked to a high quality crude suitable for further processing.

The water discharged from the hot water process must be stored, disposed of or recycled back into the process. Because this water contains bitumen emulsions, finely dispersed clay with poor settling characteristics and other contaminants, water pollution considerations prohibit discarding the water into rivers, lakes or other natural bodies of water. It has been proposed that the water be stored in evaporation ponds but this proposal would involve

2

large space requirements and the construction of expensive enclosure dikes. It has also been suggested that the water in the effluent discharge be recycled back into the process as an economic measure to conserve both heat and water. Canadian Pat. 841,581, issued May 12, 1970 to Floyd et al., teaches that some of this water can be so recycled but that the amount of recycle is limited by the dispersed silt and clay content of the water which can reduce froth yield by increasing the viscosity of the middlings layer and retarding the upward settling of bitumen flecks. A proportion of water in the diluted tar sands pulp fed into the separation cell must therefore be fresh water—water which is substantially free of the clay and silt found in middlings water. In fact, with some high clay content tar sands feeds, all of the water in the diluted pulp must be added as fresh water.

It has been found that water discharged from the process containing silt and clay can be made suitable for recycle as at least a portion of the hot water process water feed by treating the discharge according to a method of agglomeration, freezing, thawing and filtration as described herein. It is known that agglomeration by means such as flocculation, even with extended settling, cannot be used to clarify water from a hot water process. Flocculation-settling produces sludges of less than 10 weight percent solids from pondwater. It has been found by the present invention that agglomeration such as by flocculation, freezing and thawing produces solids compaction of greater than 10 weight percent solids up to about 30 weight percent. It has also been found that proper agglomeration of the pondwater must be combined with the freezing and thawing steps. Freezing and thawing alone will not produce a stable compacted sludge of more than 10 weight percent solids.

Although the present invention is not to be bound by theoretical explanation, it is believed that the freezing and thawing sequence causes solids compaction by concentration and compression of the clay agglomerates during the freezing step followed by settling of the larger and more dense agglomerates in the thawing step.

When pondwater is treated with an acid, or salts, the clay agglomerates. As freezing of the agglomerated clay slurry proceeds, ice crystals are formed thus compacting the clay among these crystals. This compaction continues until the sample is frozen solid. Upon thawing, the compacted agglomerates settle to the bottom of the container. Visual observation of the frozen treated pondwater has shown the existence of the two phases. The phases are randomly formed throughout the sample, one being clear; the other opaque. This fact suggests that a clear liquid phase and a sludge phase are being formed in the freezing step of the operation. Another fact which is consistent with this concept is the relative size distribution of solids in pondwater before and after treatment by the freezethaw cycle. The mechanism postulated above would predict that the particle sizes in the treated pondwater would be larger because of the concentration and compression of the solid during the process.

For the purpose of the present specification the term "pondwater" is defined as effluent discharge from a hot water process which effluent has been settled to give a composition comprising water containing up to about 20 percent solids, between 80 to 100 percent of which is fine clay of a size smaller than 2 microns. The effluent discharge from a hot water process comprises middlings material of depleted bitumen content which has undergone final treatment, the sand tailings layer from the process and other discharged water-containing fractions which are not the primary products of the hot water process. The discharge is removed from the process area as a slurry of about 25 to 60, typically 45, percent solids by weight. The effluent contains virtually all of the clay ma-

terial which was present in the feed. Typically, the amount is 2 to 10 weight percent of the feed. This material is smaller than 2 microns and has extremely poor settling characteristics.

The present invention is describable as an improvement to the hot water process for treating bituminous tar sands in which the hot water process comprises forming a mixture of tar sands and water, passing the mixture into a separation zone to form an upper bitumen froth layer, a middlings layer comprising water, finely divided mineral and bitumen and a sand tailings layer. The improvement comprises agglomerating finely divided minerals of at least a portion of the middlings, freezing the portion containing agglomerated finely divided minerals, thawing the portion and recovering from said thawed portion a lower sludge layer characterized by a substantially increased mineral content compared to the middlings portion and an upper clarified water layer substantially reduced in mineral content and suitable for recycle back into the hot water process as at least a portion of the water utilized to form the mixture of tar sands and water.

The present invention can be described in more detail with reference to the drawing which shows the present improvement in combination with a preferred embodiment of the hot water process.

In the figure, bituminous tar sands are fed into the system through line 1 where they first pass to a conditioning drum or muller 3. Water and steam are introduced from 2 and mixed with the sands. The total water so introduced is a minor amount based on the weight of the tar sands processed and generally is in the range of 10 to 45 percent by weight of the total mixture. Enough steam is introduced to raise the temperature in the conditioning drum to within the range of 130° to 210° F. and preferably to above 170° F. Monovalent alkaline reagents can also be added to the conditioning drum, usually in amount of from 0.1 to 3.0 pounds per ton of tar sand. The amount of such alkaline reagent preferably is regulated to maintain the pH of the middlings layer in separator zone 12 within the range of 7.5 to 9.0. Best results are obtained at a pH value of 8.0 to 8.5. The amount of the alkaline reagent that needs to be added to maintain a pH value in the range of 7.5 to 9.0 may vary from time to time as the composition of the tar sands as obtained from the mine site varies. The best alkaline reagents to use for this purpose are caustic soda, sodium, carbonate or sodium silicate, although any of the other monovalent alkaline reagents can be used if desired.

Mulling of the tar sands produces a pulp which then passes from the conditioning drum as indicated by line 4 to a screen indicated at 5. The purpose of screen 5 is to remove from the tar sand pulp any debris, rocks or oversized lumps as indicated generally at 6. The pulp then passes from screen 5 as indicated by 7 to a sump 8 where it is diluted with additional water from 9 and a middlings recycle stream 10. In the event the clay content of the tar sands is high, a relatively high rate of fresh or treated feed water introduction through 9 can be employed to compensate for the high clay introduction while a correspondingly high rate of transfer of middlings layer through line 15 as hereinafter described can be maintained. Under these circumstances recycling of the other stream of middlings through line 10 to the sump is not required.

Modifications that may be made in the process as above described include sending a minor portion of the middlings recycle stream from line 10 through a suitable line (not shown) to the conditioning drum 3 to supply all or a part of the water needed therein other than that supplied through condensation of the stream which is consumed. Also, if desired, a stream of the middlings recycle can be introduced onto the screen 5 to flush the pulp therethrough and into the sump. As a general rule, the total amount of water added to the natural bituminous sands as liquid water and as steam prior to the separation step should be in the range of 0.2 to 3.0 tons per ton of the

bituminous sands. The amount of water needed within this range increases as the silt and clay content of the bituminous sand increases. For example, when 15 percent by weight of the mineral matter of the tar sands has a particle size below 44 microns, the fresh water added generally can be about 0.3 to 0.5 ton per ton of tar sands. On the other hand, when 30 percent of the mineral matter is below 44 microns diameter, generally 0.7 to 1.0 ton of water should be used per ton of tar sands. Correspondingly the amount of bitumen-rich middlings removed through line 15 will vary depending upon the rate of fresh water addition. As a general rule, the rate of withdrawal of bitumen-rich middlings to scavenger zone 16 will be 10 to 75 gallons per ton of tar sands processed when 15 percent by weight of the mineral matter is below 44 microns and 150 to 250 gallons per ton when from 25 to 30 percent of the mineral is of this fine particle size.

Further following the process, the pulped and diluted tar sands are pumped from the sump through line 11 into the separation zone 12. This zone comprises a cell which contains a relatively quiescent body of hot water. In the cell, the diluted pulp forms into a bitumen froth layer which rises to the cell top and is withdrawn via line 13 and a sand tailings layer which settles to the bottom to be withdrawn through line 14. An aqueous middlings layer between the froth and tailings contains silt and clay and some bitumen which failed to form froth. In order to prevent the buildup of clay in the system, it is necessary to continually remove some of the middlings layer and supply enough water in the conditioning operations to compensate for that so removed. The rate at which the middlings need to be removed from the system depends upon the content of clay and silt present in the tar sands feed and this will vary from time to time as the content of these fines varies. If the clay and silt content is allowed to build up in the system, the viscosity of the middlings layer will increase. Concurrently with such increase, an increase in the proportions of both the bitumen and the sand retained by the middlings will occur. If the clay and silt content is allowed to build up too high in the system, effective separation no longer will occur and the process will become inoperative. This can be avoided by regulating the recycling and withdrawal of middlings and input of fresh water per the invention disclosed and claimed in the Floyd et al. patent. However, even when the separation step is operating properly, the middlings layer withdrawn through line 15 will contain a substantial amount of bitumen which did not separate. Hence the middlings layer withdrawn through line 15 is, for purpose of description, herein referred to as "oil-rich" or "bitumen-rich" middlings.

The oil-rich middlings stream withdrawn from separator 12 through line 15 is sent to a scavenger zone 16 wherein an air flotation operation is conducted to cause the formation of additional bitumen froth. The processing conducted in the scavenger zone 16 involves air flotation procedures conventionally utilized in processing of ores. This involves providing a controlled zone of aeration in the flotation cell at a locus where agitation of the middlings is being effected so that air becomes dispersed in the middlings in the form of small bubbles. The drawing illustrates a flotation cell of the subaeration type wherein a motorized rotary agitator is provided and air is fed thereto in controlled amount. Alternatively the air can be fed in through the shaft of the rotor. The rotor effects entraining of the air in the middlings. This air causes the formation of additional bitumen froth which passes from the scavenger zone 16 through line 17 to a froth settler zone 18. A bitumen-lean middlings stream is removed from the bottom of the scavenger zone 16 via line 19.

In the settler zone 18, the scavenger froth forms into a lower layer of settler trailings which is withdrawn and recycled via line 20 to be mixed with bitumen-rich middlings for feed to the scavenger zone 16 via line 15. In

the settler zone, an upper layer of upgraded bitumen froth forms above the tailings and is withdrawn through line 21 and is mixed with primary froth in line 13. The combined froths are at a temperature of about 160° F. They are heated with steam and diluted with sufficient naphtha or other diluent from 22 to reduce the viscosity of the bitumen for centrifuging in zone 23 to produce a bitumen product 24 suitable for further processing.

The oil-lean middlings in line 19 and the sand tailings from the separation zone 12 are combined to form an effluent discharge which is delivered via line 25 to a sand pile zone 26 via distribution piping 27. The effluent contains between 25 and 60 weight percent sand and silt material which is larger than about 2 microns. The distribution piping provides for continuous and uniform delivery of the effluent to the sand pile zones where the sand and silt material is deposited. The water in the effluent discharge percolates down through and over the sand pile zone 26 to the pond zone 28 where it collects as pondwater containing up to about 12 weight percent suspended solids, between 80 to 100 percent of which is a fine clay of a size smaller than 2 microns. The pondwater also contains between about 0.1 and 1.5 weight percent bitumen. Because of the particular composition of this pondwater, and especially because of the extreme fineness of the suspended clay material which has extremely poor settling characteristics, the water cannot be discarded or to any great extent recycled back into the hot water system.

The present invention is applied to this pondwater clarifying the water for recycle back to be mixed with the process tar sands feed. Preferably the process is conducted by introducing agglomerating agents into the pondwater followed by alternately freezing and thawing the water in the pond zone. In the present invention, increased solids compaction is obtained by one freezing-thawing cycle of agglomerated pondwater; however, it is preferred that the freezing and thawing be conducted in a plurality of cycles since it has been found that the amount of solids compaction is a function of the number of freeze-thaw cycles performed.

Through alternate freezings and thawing steps the pondwater settles into a sludge at the bottom of the pond and sets a clarified water portion near the pond surface. The sludge contains about 30 weight percent solids and the pondwater is reduced in solids content to the extent that it is suitable for recycle via line 29 back to line 9 as a portion of the water used to form the mixture of water and tar sands passed into the separation cell 12.

The treated water can be introduced via line 29 into the system as all or a portion of the water in line 9 to the sump as shown or can be alternatively introduced into the system via lines 2 or 10 or as a screen wash or at any desired point of introduction into the process.

Although the invention has been described supra with reference to the treatment of pondwater from the hot water process effluent discharge, it should be pointed out that the invention can be practiced on any water stream from the separation cell. For example, referring again to the drawing, the bitumen-lean middlings line 19 from the flotation scavenger zone 16 can be directly treated by the invention to make these middlings suitable for recycle back into the process. Also the middlings in line 10 can be

treated before recycle into sump 8 for dilution of the tar sands pulp.

The drawing shows the present invention applied to pondwater in a single zone. If desired the pondwater can be removed from the pond and agglomerated, frozen and thawed and settled in separate zones.

The agglomeration step on the pondwater can be carried out by adding a conventional agglomerating reagent to the water with gentle agitation. Among the various reagents useful for agglomerating clay are sodium and calcium chlorides, aluminum sulfate (alum), polyalkylene oxides such as polyethylene oxide, compounds of calcium such as calcium hydroxide, calcium oxide, calcium chloride, calcium nitrate, calcium acid phosphate, calcium sulfate, calcium tartrate, calcium citrate, calcium sulfonate, calcium lactate, the calcium salt of ethylene diamine tetraacetate and similar organic sequestering agents. Also suitable are guar flour or a high molecular weight acrylamide polymer such as polyacrylamide or a copolymer of acrylamide and a copolymerizable carboxylic acid such as acrylic acid. Additional flocculants include the polymers of acrylic or methacrylic acid derivatives, for example, acrylic acid, methacrylic acid, the alkali metal and ammonium salts of acrylic acid or methacrylic acid, acrylamide, methacrylamide, the aminoalkyl acrylates, the aminoalkyl acrylamides, the aminoalkyl methacrylamides and the N-alkyl substituted aminoalkyl esters of either acrylic or methacrylic acids.

Preferably agglomeration is accomplished by changing the pH of the water. Variation of pH causes a change in the charge on the edges of the clay particles, thus allowing agglomeration. The effluent discharge from the hot water process has a pH ranging from about 7.5 to 9.0 typically about 8.3. In this range, the contained mineral material is not agglomerated. Raising the pH above about 9.0 or lowering it below about 7.5 causes agglomeration. More preferably, agglomeration in zone 28 is accomplished by adding sulfuric acid (to the middlings or effluent discharge portion as the case may be) to about pH 5.

The freezing and thawing steps can be conducted by any means known in the art. Preferably however, freezing and thawing of the pondwater is conducted in the pond zone by dividing the zone into two areas. The first area is allowed to freeze by exposure to ambient temperatures below 32° F. Water being discharged from the distribution pipes through the sand zone collects in a second pond area. During periods when the ambient temperatures are greater than 32° F., the clear clarified water from the first area is discarded or recycled. The water in the second area is diverted to the first along with current runoff from the distributed pipes. This pondwater is collected until again average ambient temperature falls below 32° F.

Another approach is to alternatively add warm water at various ends of a frozen pond at certain intervals over a period when the ambient temperature is below 32° F. This approach results in repeated freezing and thawing-settling cycles. Another method of conducting the freezing-thawing-settling technique of the present invention is to circulate water from beneath frozen pondwater to the surface of the ice accompanied by addition of additional runoff water either to beneath or onto the surface of the ice.

The following examples illustrate the invention:

TABLE I

Reagent	Feed, wt. percent	Sludge, wt. percent clay	Reagent dosage, ¹ pounds/1,000 gallons			Note
			Clear	Cloudy		
Al ₂ (SO ₄) ₃	6.5	19.7	13.8	5.5		
	12.0	15.8	13.8	5.5		
FeCl ₃	6.5	13.0	7.14	3.5		
	12.0	10.3	9.17	4.5		
CaCl ₂	6.5	18.1	9.17	4.5		
	12.0	26.6	5.05	3.33	pH=4.5	
H ₂ SO ₄	6.5	23.2		2.5.05	pH=5.0	
None	6.5	6.5				

¹ Intermediate dosages not tested. "Clear" indicates sample settled within 1 hour to produce clear supernatant. "Cloudy" supernatants did not settle further within 1 week.

² Supernatant settled clear within 48 hours.

Several freeze-thaw runs on pondwater from a hot water process for separating bitumen from tar sands are reported in Tables I and II. In Table I pondwater feeds of various weight percent clays were treated with various agglomerating agents, then frozen, thawed and settled and compared to an untreated sample. The results in Table I indicate that various agglomerating agents can be used in the present invention and that the process of the present invention is applicable to the clarification of pondwaters of various clay compositions.

The runs in Table II were made on pondwater containing 6.5 weight percent clay to determine the extent of sludge compaction for repeated freeze-thaw cycles. These runs show that it is possible to achieve compactions of 30 weight percent solids by using the process of the present invention.

TABLE II

Freeze-thaw cycles completed	Weight percent solids in sludge		
	Test 1, 5.05 pounds H ₂ SO ₄ /1,000 gallons	Test 2, 5.05 pounds H ₂ SO ₄ /1,000 gallons	Test 3, 13.8 pounds Al ₂ (SO ₄) ₃ /1,000 gallons
1-----	9	21.6	8.1
2-----	30.7	29.5	8.1
3-----		30.5	29.1

The embodiments of the invention in which an exclusive property or privilege is claimed are defined as follows:

1. In a hot water process for treating bituminous tar sands which comprises: forming a mixture of tar sands and water; passing said mixture into a separation zone to form an upper bitumen froth layer, a middlings layer comprising water, finely divided mineral and bitumen and a sand tailings layer; and separately removing said bitumen froth layer, middlings layer and tailings layer; the improvement which comprises:

- (a) agglomerating finely divided mineral of at least a portion of the middlings;
- (b) freezing the portion of middlings containing agglomerated finely divided mineral;
- (c) thawing the frozen middlings portion and
- (d) recovering from a thawed portion a lower sludge layer characterized by a substantially increased mineral content compared to said middlings portion and an upper clarified water layer substantially reduced in mineral content.

2. The process of claim 1 in which the agglomerating step comprises adding an agglomerating agent to agglomerate said mineral component.

3. The process of claim 1 in which the agglomeration step comprises adjusting the pH of said middlings portion below about 7.5.

4. The process of claim 1 in which the agglomeration step comprises adjusting the pH of said middlings portion to above about 9.0.

5. The process of claim 1 in which said water layer substantially reduced in mineral content is recycled back

into the hot water process as at least a portion of the water utilized to form said mixture of tar sands and water.

6. The process of claim 1 in which said freezing and thawing steps are repeated.

7. The process of claim 1 in which said lower sludge layer of step (d) comprises greater than 10 weight percent solids.

8. In the hot water process for treating bituminous tar sands which comprises: forming a mixture of bituminous sands and water; passing the mixture to a separation zone to form an upper bitumen froth layer, a middlings layer comprising water, clay and some bitumen and a sand tailings layer; recovering said froth layer; and passing at least a portion of the middlings layer and tailings layer to a settling pond zone; the improvement which comprises:

- (a) agglomerating the clay in at least a portion of the water contained in said settling pond zone;
- (b) freezing said portion containing agglomerated finely divided mineral;
- (c) thawing said frozen portion and
- (d) recovering from said thawed portion a lower sludge layer characterized by a substantially increased mineral content compared to said middlings portion and an upper clarified water layer substantially reduced in mineral content and suitable for recycle back into the hot water process as at least a portion of the water utilized to form said mixture of tar sands and water.

9. The process of claim 8 in which the agglomeration step comprises adding an agglomerating agent to agglomerate said mineral component.

10. The process of claim 8 in which the agglomeration step comprises adjusting the pH of said middlings portion below about 7.5.

11. The process of claim 8 in which the agglomeration step comprises adjusting the pH of said middlings portion to above about 9.0.

12. The process of claim 8 in which said water layer substantially reduced in mineral content is recycled back into the hot water process as at least a portion of the water utilized to form said mixture of tar sands and water.

13. The process of claim 8 in which said freezing and thawing steps are repeated.

14. The process of claim 8 in which said lower sludge layer of step (d) comprises greater than 10 weight percent solids.
